UNITED STATES PATENT OFFICE.

SAMUEL N. BARKER, OF KALAMAZOO, MICHIGAN.

DESIGN FOR A BACK FOR PLAYING-CARDS.

No. 37,789.

Specification for Design.

Patented Jan. 16, 1906.

Application filed November 9, 1905. Serial No. 286,615. Term of patent 14 years.

To all whom it may concern:

Be it known that I, SAMUEL N. BARKER, a citizen of the United States, residing at the city of Kalamazoo, in the county of Kalamazoo and State of Michigan, have invented a new, original, and ornamental Design for a Back for Playing-Cards.

My new, original, and ornamental design for a playing-card is clearly illustrated in the accompanying drawing, which is a plan view thereof.

I claim—

The ornamental design for a back for playing-cards, as shown.

SAMUEL N. BARKER.
